(57) **CLAIM**

The ornamental design for an LED light fixture with cross-mounted modules, as shown and described.

DESCRIPTION

FIG. 1 is a perspective view from below of the LED light fixture with cross-mounted modules, the details of the underside of each module, a mounting arm and a pole being shown in phantom lines;

FIG. 2 is a perspective view from above of the LED light fixture with cross-mounted modules of FIG. 1;

FIG. 3 is a rear elevation view of the LED light fixture with cross-mounted modules;

FIG. 4 is a bottom plan view of the LED light fixture with cross-mounted modules of FIG. 1;

FIG. 5 is a top plan view of the LED light fixture with cross-mounted modules of FIG. 1;

FIG. 6 is a right-side elevation of the LED light fixture with cross-mounted modules, the left-side elevation being a mirror image;

FIG. 7 is another a perspective view from below of the LED light fixture with cross-mounted modules of FIG. 1; and,

FIG. 8 is a front perspective view from below of the LED light fixture with cross-mounted modules of FIG. 1.

The phantom lines are provided for illustrative purposes only and form no part of the claimed design.
